UNITED STATES PATENT OFFICE

155,309

DESIGN FOR A HAIR WAVE FLUID APPLICATOR OR SIMILAR ARTICLE

Morris Morrison, Chicago, Ill., assignor to Morrison-Atlas Products, Chicago, Ill., a copartnership

Application July 3, 1948, Serial No. 147,366

Term of patent 7 years

(Cl. D86—10)

To all whom it may concern:

Be it known that I, Morris Morrison, a citizen of the United States, and a resident of the city of Chicago, in the county of Cook and State of Illinois, have invented a new, original, and ornamental Design for a Hair Wave Fluid Applicator or Similar Article, of which the following is a specification, reference being had to the accompanying drawing, forming a part thereof.

On the drawing:

Figure 1 is an elevational view of the hair wave fluid applicator or similar article, showing my new design; and

Figure 2 is a side elevational view thereof, the swab being omitted in this view.

The essential feature of my design resides in the handle shown in full line.

I claim:

The ornamental design for a hair wave fluid applicator or similar article, as shown and described.

MORRIS MORRISON.
